UNITED STATES PATENT OFFICE

134,507

DESIGN FOR A COMBINED PERFUME BOTTLE AND HOLDER THEREFOR

Walter Hershfield, New York, N. Y., assignor to Artfield Creations, Inc., New York, N. Y., a corporation of New York

Application April 1, 1941, Serial No. 100,075

Term of patent 3½ years

To all whom it may concern:

Be it known that I, Walter Hershfield, a citizen of the United States and a resident of the city of New York (Borough of Manhattan), county of New York, and State of New York, have invented a new, original, and ornamental Design for a Combined Perfume Bottle and Holder Therefor, of which the following is a specification, reference being had to the accompanying drawing forming part thereof, in which—

Figure 1 is a perspective view in open position showing the top, rear end and side of a combined perfume bottle and holder therefor embodying my new design;

The side of the holder not shown bears substantially the same ornamentation thereon as the side shown.

I claim:

The ornamental design for a combined perfume bottle and holder therefor, substantially as shown and described.

WALTER HERSHFIELD.
